UNITED STATES PATENT OFFICE.

MARTIN KLIMA, OF TABOR, ASSIGNOR OF ONE-HALF TO JOHN CHARMOCK,
OF RACINE, WISCONSIN.

FEED-CUTTER.

SPECIFICATION forming part of Letters Patent No. 279,096, dated June 5, 1883.

Application filed November 21, 1882. (No model.)

To all whom it may concern:

Be it known that I, MARTIN KLIMA, of Tabor P. O., in the county of Racine, and in the State of Wisconsin, have invented certain new and useful Improvements in Feed-Cutters; and I do hereby declare that the following is a full, clear, and exact description thereof.

My invention relates to feed-cutters; and it consists in certain peculiarities of construction, so as will be fully set forth hereinafter.

In the drawings, Figure 1 is a perspective of my entire machine. Fig. 2 is a plan view, with a portion of the hood broken away. Fig. 3 is a detail sectional view, and Fig. 4 is a detail view in elevation.

A represents the frame of the machine, and may be either of wood or metal, as preferred; and this frame consists of four uprights, A' A² A³ A⁴, with upper cross-pieces, a a' a² a³, and preferably lower strengthening cross-pieces.

B B are journal-boxes mounted on the cross-pieces a a³, and having bearings to receive shaft C, which shaft supports at one end the cutter-wheel C', just outside the journal-box at that end.

D' is a lever pivoted to the cross-piece a² at e, and extending under the shaft C, at right angles thereto, beyond the outer edge of the cross-piece a', the forward end of said lever moving in a covered groove or slot, E, formed in said piece a', near the corner-post A' of the frame A. At a point on said lever opposite the cam D a small horizontal wheel or friction-roller, d', is located, supported between flat plates or bearings d d, secured to the lever D', which wheel bears against the inner concave surface of the cam D and causes the lever to move laterally toward and from the cutter-wheel C' as the cam is revolved. The outer or free end of this lever D' is pivoted to one end of a pawl, F, whose other end engages with the teeth on a ratchet-wheel, F', while a second pawl, F², is pivoted to the cross-piece a', and its free end engages with the teeth of said ratchet-wheel below the first-named pawl and serves to prevent any backward motion of the said ratchet-wheel. Both of these pawls pass between the sides of an upright loop or guide, f, secured to the cross-piece a'.

The ratchet-wheel F' is mounted upon a shaft, G', which extends entirely across the frame, and bears upon its op-

posite end, just within the frame, the lower feed-roller, H', while on the same end that carries the ratchet-wheel, but within the frame, the shaft has a small gear-wheel, g', rigidly keyed to it. Above this shaft is a shaft, G, one end of which carries the upper feed-roller, H, and which has near its other end the small gear-wheel g, directly above and meshing with the gear g'. In order to permit the feed-rollers to yield and separate, this shaft G is made in two parts, united by a universal joint at h, and the said shaft is normally inclined upward at a slight angle from the joint h to the gear g, while the lower shaft, G', is horizontal. The extreme end of the upper shaft, G, has a sleeve, I, secured to it, with downward-projecting lug i, which is pivoted between the forks of a bifurcated arm, I', rising from the cross-piece a', so as to allow some longitudinal play to the shaft G as its feed-roller H rises or falls.

K represents my feed-trough, converging from the entrance end toward its throat, and there provided with a heavy metal block, L, whose purpose is to bear down upon the hay, straw, or other feed after it has passed between the feed-rollers, so as to compress it into a compact mass for the cutters to operate upon; and to further insure such compression I have provided the metal strap b, having a central horizontal portion secured to the block L, after which the strap rises at each end and passes up along the inner side of the throat of the trough K, and then passes down along the outside of said trough to a point below it and below the lower feed-roller, where the two ends of said strap l are united by a short shaft, M, which serves as a fulcrum to the lever N, pivoted at n to the cross-piece a, and whose farther end extends nearly to the cross-piece a³, and is provided with notches n' n' to receive a weight, N'. By changing this weight from notch to notch the leverage can be increased or diminished at will, and consequently the pressure of the block L upon the feed to be cut will be likewise increased or diminished correspondingly.

O designates a hood placed over the throat end of the trough, so as to prevent the hay or other feed from falling over the sides of the trough as it is being pushed forward to the feed-rollers.

The cutter-wheel C consists of a heavy metal ring or open disk, divided into two parts by the strip c', through the center of which it is journaled on the end of the shaft C, as already described. The wheel is provided with two curved knives, P P, securely bolted to the widest parts, one on each side of the strip c', as shown. Power is communicated to this wheel by hand at c; or, if desired, the shaft C may be extended beyond the cross-piece a' and a crank applied thereto in any convenient manner.

In order to apply horse or steam power, I have provided the shaft C with a bevel-gear wheel, q', which meshes with a similar bevel-gear, q, on the end of a shaft, Q, supported in the bearings B' B', rising, respectively, from central cross-piece, a', and the cross-piece a'. On the outer end of this shaft an ordinary belt-pulley, R, may be applied, as shown in Fig. 2, to communicate with the power desired, or here an ordinary crank may be secured, as in Fig. 1, when it would be inconvenient to turn the wheel from the handle c.

The cutter-wheel C' is mounted on the shaft C in such relation to the cam D that the knives will not cut while the cam is operating to rotate the rollers H H' and feed the hay, &c., forward; but the moment the feed is completed the block L will hold the hay, &c., stationary in a compressed state, and then one of the knives will begin to cut, and as its cut is completed the cam D will begin to operate by forcing the lever D' forward and setting in motion the feeding mechanism, which will stop in turn just as the other knife is brought around to begin its cut, and so on.

The length of the cut feed is regulated by means of the thumb-screw S, passing through the corner-post A' and bearing against the lever D', which in turn is kept against the end of this screw by means of spring T on the inside of cross-piece a', as best indicated by dotted lines in Fig. 1. By screwing this part S in or out, the distance back that the lever D' is permitted to travel is regulated, and hence the number of teeth on the ratchet F' moved by the pawl F at each revolution of the shaft C is determined, and consequently the revolution of the feed-rollers is thereby controlled, making the length of the cut feed variable at the will of the operator by a simple movement of the said set-screw.

The described shafts G and G', which carry the feed-rollers H and H', pass through slots l' in the strap l, and through other slots or holes cut in the sides of the throat of the trough K, and the upright portions of the said strap, just at the top of the slots l', straddle and slightly bear on the upper shaft, G, so that as the said shaft and upper feed-roller, H, yield upwardly the strap will also be carried upward, carrying with it the block L, and hence permitting the feed to pass under the said block to be cut.

I am aware that it is not new to construct

feed-cutters in such manner that they will feed and cut alternately; and I am also aware that feed-cutters having been made carrying a cutter-wheel similar to mine, the shaft of which was provided with a cam connecting with a ratchet-wheel mounted on the shaft of one of the feed-rollers and provided with suitable pawls and dogs, whereby the said alternate feed and cutting was accomplished. I am also aware that feed-cutters have been provided with various devices for adjusting and regulating the length of the cut, and also with weights and springs to regulate the pressure of the feed-rollers upon the straw or other material passing therethrough, and hence I do not claim any of these features, broadly; but,

Having thus described my invention, what I claim as new, and desire to secure by Letters Patent, is—

1. The combination, in a feed-cutter, of the shaft C, cutter-wheel C', cam D, lever D', extending under shaft C at right angles thereto, and provided with plates d d, and horizontal wheel d, journaled between said plates, pawl F, ratchet-wheel F', and the feed-rollers and their shafts and connecting mechanism, substantially as set forth.

2. The combination, in a feed-cutter, of the feed-rollers H H', shafts G G', gear-wheels g g', the lower shaft, G', being horizontal, while the upper shaft, G, is made in two parts united by joint h, one part being inclined upward at a slight angle from the joint h to the gear g, slotted strap l l', block L, sleeve I, having lug i pivoted between the forks of arm I', and actuating mechanism, substantially as set forth.

3. The combination, in a feed-cutter, of the feed-rollers and their shafts with the block L, slotted strap l l', having an upper central horizontal portion secured to said block, and two depending ends united by shaft M, pivoted and notched lever N, and weight N', substantially as set forth.

4. The combination of the frame of the feed-cutter with the trough K, feed-rollers H and H', shafts G and G', heavy metal block L, closing up the entire throat of the trough in front of the feed-rollers, continuous metal strap l, secured to the top of block L, and then passing up along the inside of trough and over and down along each outer side, and having slots l' to receive the feed-roller shafts, and with the depending ends of said strap united below the trough by shaft M, which passes through lever N, the said lever being pivoted to the frame at a, and provided with notches n', and weight N', all substantially as set forth.

In testimony that I claim the foregoing I have hereunto set my hand, on this 21st day of September, 1882, in the presence of two witnesses.

MARTIN KLIMA.
